United States Patent Office

Des. 191,836
Patented Nov. 28, 1961

191,836

SAUCEPAN

John W. Ebstein, Roslyn Heights, N.Y., assignor to Federal Enameling & Stamping Co., Pittsburgh, Pa., a corporation of Michigan

Filed Sept. 12, 1960, Ser. No. 62,109

Term of patent 14 years

(Cl. D44—1)

FIG. 3. FIG. 4. FIG. 5. FIG. 6.

FIGURES 3, 4, 5 and 6 are cross-sectional views on the correspondingly numbered section lines in FIGURE 1.

The dominant features of my design are shown in full lines.

I claim:

The ornamental design for a saucepan, as shown and described.
